(57) **CLAIM**

The ornamental design for a purse base shaper, as shown and described.

DESCRIPTION

FIG. 1 is a top plan view of a purse base shaper showing my new design.

FIG. 2 is a bottom plan view of the purse base shaper.

FIG. 3 is an upper perspective view of the purse base shaper.

FIG. 4 is a lower perspective view of the purse base shaper.

FIG. 5 is a front view of the purse base shaper, the rear view

being a mirror image; and,

FIG. 6 is a right side view of the purse base shaper, the left side view being a mirror image.

Lightly weighted lines are shading lines which illustrate contour.

1 Claim, 3 Drawing Sheets
